MEMORIAL WALL PLAQUE OR THE LIKE

Philip Karz, 1035 Westholme Ave.,
Los Angeles, Calif. 90024

Filed Sept. 22, 1965, Ser. No. 87,120

Term of patent 14 years

(Cl. D29—23)

I claim:

The ornamental design for a memorial wall plaque or the like, as shown.
